UNITED STATES PATENT OFFICE.

JOSEPH A. IMHOF, OF NEW YORK, AND JOHN CHARTERS, OF ASTORIA, NEW YORK,
ASSIGNORS TO INVISIBLE COLOR PRINT CORPORATION, OF NEW YORK, N. Y., A
CORPORATION OF NEW YORK.

PRINT AND PROCESS OF MAKING SAME.

Application filed October 31, 1922. Serial No. 598,081.

To all whom it may concern:

Be it known that we, JOSEPH A. IMHOF and JOHN CHARTERS, citizens of the United States, the former a resident of New York 5 city, in the borough of Manhattan, county and State of New York, and the latter a resident of Astoria, Long Island City, in the county of Queens and State of New York, have invented certain new and useful Im- 10 provements in Prints and Processes of Mak- ing Same, of which the following is a speci- fication.

This invention relates to a print having a disguised image which subsequently can be 15 rendered visible and to the process of producing the same.

In the prior art of making prints, hidden images have been produced in various ways and have been rendered visible by the use of 20 chemicals. The main object and feature of the present invention is to render the hidden object visible by the application of water without the use of special chemicals.

In the accompanying drawings the invention 25 is embodied in several concrete and preferred forms in which

Figs. 1, 2, 3 and 4 show the steps of one 30 form of the invention for producing a print with a hidden image and the revealing of the same.

Figs. 5, 6, 7 and 8 show the steps of another form of the invention for producing a print with a hidden image and the revealing of the same.

Figs. 9 to 14 show other forms of the invention in which the latter is combined with the invention of Letters Patent No. 1,384,663 35 of July 12, 1921.

Fig. 9 shows the yellow impression.

Fig. 10 shows the red impression.

Fig. 11 shows the blue impression.

Fig. 12 shows the outline impression in black.

Fig. 13 shows the stop color or invisible 45 impression.

Fig. 14 shows the assembly of Figs. 9 to 18 inclusive after the water is applied.

Figs. 15 and 16 show still another form 50 of the invention before and after the water is applied.

Considering first Figs. 1 to 4 inclusive 1 indicates a printing surface of paper or other material capable of receiving impressions. In Fig. 2 this surface is shown as

having received an impression indicated for 55 convenience by section lines 2 which forms a visible image, in this instance covering the entire surface 1. This impression is made with ink consisting wholly of or carrying latent coloring matter such as aniline dye 60 soluble in water as explained in Patent No. 1,384,663 dated July 12, 1921. It will be understood that a single color only need be used and that this color may be the same as the oily body carrying the same if such be 65 employed. And further that the printing may be solid as when produced from a printing surface of uniform height or the printing may be produced by printing from half-tone plates or the like such as Ben Day 70 plates. Superposed on the image formed by the impression thus produced is a substantially invisible impression forming image 3 indicated by the word "President" 75 in dotted outline in Fig. 3. This image is made preferably with an impression of translucent varnish through which image 2 shows and image 3 is therefore both insoluble in water and invisible. The impression of image 3 may be made either from a 80 solid form or from half-tone plates or the like. If desired the varnish may be slightly tinted so as to match as near as possible the color or tone of the surface 1 before printing. The tint thus used may be a white oil 85 ink. It will now be understood that, when water is applied to the surface of the print, the varnish impression will act to stop-out the color of the underlying soluble impression while the exposed parts of the latter 90 will be dissolved and the color released. By contrast of color, therefore, the invisible image 3 will appear or emerge as shown in Fig. 4. It will be understood that the invisible image may be either lettering or other 95 design such as a picture and that the stop-out may be either of the background or of the image so long as the color contrast is produced. In case the stop-out impression is printed from a half-tone plate some 100 of the color of the underlying visible image will be released but not so abundantly as the exposed parts of the visible image and there will therefore be enough difference in tone 105 between the exposed and stopped-out parts to render the emergence of the invisible image effective.

Under certain conditions and with certain

classes of paper, notably newsprint paper, it is desirable to reverse the process just described and to proceed as shown in Figs. 5 to 8 inclusive. As there shown the surface 5 receiving the impression is indicated by 1, and upon this surface is impressed, first, invisible image 3 (Fig. 6). Then the visible image 2 is superposed on the invisible image (Fig. 7) and finally water is applied to cause 10 the invisible image to emerge (Fig. 8). In this form of the invention the invisible image printed in varnish tends to prevent the sinking in of the ink or coloring matter of the visible image. Consequently when water 15 is subsequently applied the ink overlying the invisible image is washed off in whole or in part thereby setting up the color contrast necessary to reveal the invisible image.

By means of the preceding examples the 20 invention has been explained in its simplest embodiment. It will be evident however that its ramifications are very extensive, especially when combined with the process of invisible color printing disclosed in Patent 25 No. 1,384,663 dated July 12, 1921. In Figs. 9, 10 and 11 are shown respectively the yellow, red and blue components 4, 5 and 6 of a picture. These components are shown as 30 being printed from half-tone plates and carry latent coloring matter. When superposed they present an image of apparently uniform color. Fig. 12 shows an outline impression 7 in black oil ink which is superposed on the other impressions, and Fig. 13 35 is the stop-color or invisible image impression 8. As will be seen here the invisible image is produced by stopping-out a part of the background surrounding the mannikin 9. When the impressions of Figs. 9 to 13 inclusive 40 are superposed an effect (except for greater detail) approximating the image of Fig. 12 is produced, and this image is of an apparently uniform color. When water is applied the coloring matter is released producing different colors and turning the moon 45 10 into a mannikin 9 as shown in Fig. 14. It will be noted that some of the stop color is printed on the two boys, especially on their heads 8^a and on the upper portions of 50 their backs 8^b as well as on the pants 8^c on the pants of one of the boys. The function of the stop-out color at these points is to increase the high lights by preventing the release of the latent coloring matter.

In Figs. 15 and 16 is shown still another 55 form of the invention. Here a number of visible impressions 11 of apparently uniform color, having latent color, an invisible stop-out color (indicated at 12 in Fig. 16), 60 and a visible image 13 in black ink are superposed. The visible image in black ink is here (Fig. 15) what appears to be the outline of clouds or shrubbery. When water is applied (Fig. 16) the invisible image 12 of a 65 man emerges in outline as shown and the

different parts of the visible image are colored differently. Thus the lower part 14 of the picture may be green, the trousers 15 brown, the coat 16 blue, the portions 17 adjacent the body and below the arms yellow, the 70 hands and face flesh-colored and perhaps variously tinted and the portions 18 adjacent the head and above the arms greenish-blue. Now in this instance of the invention the visible image 13 in black ink, i. e., the outline of clouds or shrubbery, serves to disguise a possible variation in appearance due to a mingling of dots of two different plates that may take place. Where two partial images meet when faulty registration occurs, 80 such faulty registration causes the images to overlap thereby possibly revealing by increase in the number of dots the outline of the invisible image.

We claim:

1. As a new article of manufacture: a print having a plurality of superimposed impressions, one of which is visible and soluble in water and another of which is insoluble in water and substantially invisible.

2. As a new article of manufacture: a print, of apparently uniform color, having a plurality of superimposed impressions two or more of which form a visible image containing latent and different coloring matter 95 soluble in water and another of which is insoluble in water and substantially invisible.

3. As a new article of manufacture: a print having a visible image formed by an impression containing matter that is soluble 100 in water, and having a substantially invisible image formed by an impression insoluble in water, the two impressions being superimposed one upon the other.

4. As a new article of manufacture: a 105 print having a visible image of apparently uniform color formed by a plurality of impressions that contain latent and different coloring matter soluble in water, and having a substantially invisible image formed 110 by an impression insoluble in water.

5. As a new article of manufacture: a print having a plurality of superimposed impressions forming a visible image and a substantially invisible image, the invisible 115 image being rendered visible by contrast in color of the images upon application of water to the surface of the print.

6. As a new article of manufacture: a print having a plurality of superimposed 120 impressions, one of which is visible and contains matter soluble in water and another of which is a translucent varnish.

7. As a new article of manufacture: a print of apparently uniform color, having a 125 plurality of superimposed impressions two or more of which form a visible image containing latent and different coloring matter soluble in water, and another of which is a translucent varnish.

8. As a new article of manufacture: a print having a plurality of superimposed impressions forming a visible image, and an invisible image printed with a translucent varnish, the invisible image being rendered visible by contrast in color of the images upon application of water to the surface of the print.

9. The method of disguising and of subsequently rendering apparent a design in a printed product which consists in printing a plurality of impressions on a surface, one of said impressions, being visible and containing matter soluble in water, and another of said impressions being insoluble in water and substantially invisible, and in then applying water to said surface to render the invisible impression visible by a contrast in color of the several impressions.

10. The method of disguising and of subsequently rendering apparent a design in a printed product which consists in printing a plurality of superimposed impressions on a surface, one of said impressions being visible and containing matter soluble in water, and another of said impressions being insoluble in water and substantially invisible, and then applying water to said surface to render the invisible impression visible by a contrast in color of the several impressions.

11. The method of disguising and of subsequently rendering apparent a design in a printed product which consists in printing upon a surface a plurality of impressions two of which have latent and different coloring matter soluble in water but presenting an image of apparently uniform color, and another of which is insoluble in water and forming a substantially invisible image, and then applying water to said surface to render the invisible image visible by a contrast in color of the several images.

12. The method of disguising and of subsequently rendering apparent a design in a printed product which consists in imprinting, on a surface, a visible image formed by an impression soluble upon application of water, then imprinting upon said surface in superimposed relation to the first impression, another substantially invisible image formed by an impression insoluble in water, and then applying water to said surface to dissolve the exposed parts of the image of the first impression to thereby render the image of the second impression visible by a contrast in colors between the two images.

13. The method of disguising and of subsequently rendering apparent a design in a printed product which consists in printing a plurality of impressions on a surface, one of said impressions being visible and containing matter soluble in water, and another of said impressions being of translucent varnish and therefore invisible and insoluble in water, and in then applying water to said surface to render the invisible impression visible by a contrast in color of the several impressions.

14. The method of disguising and of subsequently rendering apparent a design in a printed product which consists in printing a plurality of superimposed impressions on a surface, of said impressions being visible and containing matter soluble in water, and another of said impressions being of translucent varnish and therefore invisible and insoluble in water, and in then applying water to said surface to render the invisible impression visible by a contrast in color of the several impressions.

15. The method of disguising and of subsequently rendering apparent a design in a printed product which consists in printing upon a surface a plurality of impressions two of which have latent and different coloring matter soluble in water but presenting an image of apparently uniform color, and another of said impressions being of translucent varnish and therefore invisible and insoluble in water, and in then applying water to said surface to render the invisible impression visible by a contrast in color of the several impressions.

16. The method of disguising and of subsequently rendering apparent a design in a printed product which consists in imprinting, on a surface, a visible image formed by an impression soluble upon application of water, then imprinting upon said surface, in superimposed relation to the first impression, another substantially invisible image formed by an impression of translucent varnish, and then applying water to said surface to dissolve the exposed parts of the image of the first impression to thereby render the image of the second impression visible by a contrast in colors between the two images.

17. As a new article of manufacture a print having a plurality of impressions, two or more of which form a visible image of apparently uniform color but containing latent and different coloring matter, soluble in water, another impression, insoluble in water, forming a visible image and acting to disguise the overlapping of adjacent edges of the two first impressions, and still another and insoluble impression forming an invisible image, whereby the three images merge into a unitary image having color contrasts when water is applied to the surface of the print.

Signed at New York city, in the borough of Manhattan, county and State of New York, this 24 day of October, 1922.

JOSEPH A. IMHOF.
JOHN CHARTERS.
